UNITED STATES PATENT OFFICE.

SAMUEL E. CREASEY, OF SANFORD, MAINE.

CALENDAR-BANK.

No. 847,652.

Specification of Letters Patent.

Patented March 19, 1907.

Application filed December 20, 1906. Serial No. 348,726.

To all whom it may concern:

Be it known that I, SAMUEL E. CREASEY, a citizen of the United States, residing at Sanford, county of York, and State of Maine, have invented an Improvement in Calendar-Banks, of which the following description, in connection with the accompanying drawing, is a specification, like letters on the drawing representing like parts.

10 This invention relates to a calendar-bank or a bank designed for the saving of money by putting aside coins at regular periods—as, for example, daily—and is arranged to serve as a constant reminder of the time for the putting aside of the coin.

15 The object of the invention is to provide such a bank which will be simple and cheap in its construction.

20 The invention will be more fully understood from the accompanying description and drawings and will be particularly pointed out in the claims.

25 The drawings represent the invention in its preferred form suitable for hanging upon the wall in place of an ordinary calendar.

30 In the drawings, Figure 1 is a front elevation of the device embodying the invention. Fig. 2 is a longitudinal vertical cross-section showing a detail of a modified form of construction. Fig. 3 is a longitudinal central vertical cross-section of the construction shown in Fig. 1.

35 In the drawings, A represents a support for the parts of the device, which may be of any suitable form, construction, and material, but is herein shown as a flat rectangular plate of pasteboard or thin wood. At the lower end of the support is fastened a box B, which is to serve as the receptacle for the 40 coins and which also may be of any suitable shape, construction, or material. Since these banks are primarily designed to be cheap and to be thrown away at the end of some stated period, such as a year, the box B is made a permanent part of the support by some ordinary fastening means unnecessary to describe. The front of the box may be ornamented or inscribed with any advertisement or legend desired. At the top 45 the box is open and provided with a downwardly-swinging cover C for the admission of the coins and extending the whole length of the box. This cover should be weighted or controlled by a spring, as shown at D, so that if the bank should be tipped upside down the cover will close and prevent the coins from

falling out and so that the cover will normally remain closed.

Above the box B and mounted upon the support A is placed a calendar-pad, the leaves of which are shown at E in Fig. 3 and which preferably takes the form of the ordinary calendar, where each sheet represents one month.

Over the calendar-pad E and preferably substantially coinciding with it in dimensions and outline is placed a face-plate F, having a series of openings G corresponding to the number of the days and allowing these numbers to show through. These openings G are preferably circular and of a size equal to that of the largest coin for which the bank is intended to be used. This face-plate F may be made of any suitable material and when made comparatively thin some means are desirable, if not necessary, to keep the coins from falling out, for the entire device is intended to be hung in a vertical position, as in the case of the ordinary calendar. If the face-plate F is made of pasteboard or some thin material, tabs g may be struck out from the periphery of the openings G, so as to catch the edge of the coin and retain it. If the plate is made of thicker material, as a thin sheet of wood, the construction shown in Fig. 2 may be employed, where the recess or opening for the coin is enlarged at the lower and rear portion, as at g'. Any suitable means for retaining the coin in place may be used. Other openings, as desired, are made in the face-plate F for allowing any other words or legends—as, for example, the name of the month and the names of the days of the week—to appear.

45 The face-plate F is pivotally mounted upon and clamped to the support by any suitable means, such as an ordinary thumb-nut H and clamping-screw H'. The only feature of this device is that the screw H' shall be held from movement when the nut is turned, and this may be secured by striking up points h from the head of the screw H' into the rear of the support A. The face-plate is also preferably held at the bottom by a small pivoted spring-clamp K, which is turned and sprung over the lower edge of the face-plate to hold it in position.

50 The operation of the device will be apparent. The calendar-bank is hung upon the wall and a coin—for example, a cent—is placed from day to day in the proper opening through which the day of the month ap-

pears. In this way the person desiring to save, for example, a penny a day will be constantly reminded as to whether or not he has put aside the proper coin, for whenever 5 he looks at the calendar he will see whether or not the current day is covered by its coin. When the month is ended, all the numbers appearing through the face-plate F will be covered by the coin. The thumb-nut H is 10 then loosened, the clamp K released, and the face-plate F swung forward, allowing the coins all together to drop down into the box B, pushing aside the swinging lid C. A sheet is then removed from the calendar-pad and 15 the face-plate again locked in position by the thumb-screw H and the clamp K, and the bank is ready to receive the coins for another month.

Having fully described my invention, what 20 I claim as new, and desire to secure by Letters Patent, is—

1. A calendar-bank comprising a support, a calendar mounted thereon, a face-plate for 25 said calendar provided with coin-receiving openings corresponding to the numbers of the calendar, means for locking the face-plate in position over the calendar and unlocking it to permit the coins to fall out at the back of the plate, a coin-receiving box 30 below the calendar mounted on the support.

2. A calendar-bank comprising a support, a calendar mounted thereon, a face-plate for 35 said calendar provided with coin-receiving openings corresponding to the numbers of the calendar, means for locking the face-plate in position over the calendar and unlocking it to permit the coins to fall out at the back of the plate, a coin-receiving box below the calendar mounted on the support, a swinging door at the top of said box adapted to 40 yield under the weight of the coins.

3. A calendar-bank comprising a support, a calendar mounted thereon, a face-plate for 45 said calendar provided with coin-receiving openings corresponding to the numbers of

the calendar, means for preventing the coins from falling out when inserted in the coin-receiving openings to cover the numbers, means for locking the face-plate in position over the calendar and unlocking it to permit 50 the coins to fall out at the back of the plate, a coin-receiving box below the calendar mounted on the support.

4. A calendar-bank comprising a support, a calendar-pad mounted thereon, a face-plate for said calendar-pad provided with 55 coin-receiving openings corresponding to the numbers on the calendar, means for preventing the coins from falling out when inserted in the coin-receiving openings to cover the 60 numbers, means for locking the face-plate in position over the pad, and unlocking it to permit the coins to fall out at the back of the plate and to permit the change or removal of a sheet of the pad, a coin-receiving box below 65 the calendar-pad mounted on the support.

5. A calendar-bank comprising a support, a calendar-pad mounted thereon, a face-plate for said calendar-pad provided with 70 coin-receiving openings corresponding to the numbers on the calendar, means for preventing the coins from falling out when inserted in the coin-receiving openings to cover the numbers, means for locking the face-plate in position over the pad, and unlocking it to 75 permit the coins to fall out at the back of the plate and to permit the change or removal of a sheet of the pad, a coin-receiving box below the calendar-pad mounted on the support, a swinging spring-controlled door at 80 the top of the said box adapted to yield under the weight of the coins.

In testimony whereof I have signed my name to this specification in the presence of two subscribing witnesses.

SAMUEL E. CREASEY.
